UNITED STATES PATENT OFFICE

ROBERT BETTS, OF LONDON, ENGLAND

DESIGN FOR A PERFUME BOTTLE OR SIMILAR ARTICLE

Application filed April 30, 1931. Serial No. 39,662. Term of patent 7 years.

To all whom it may concern:

Be it known that I, ROBERT BETTS, a subject of the King of Great Britain, residing at 35/39 Maddox Street, Regent Street, London, England, have invented a new, original, and ornamental Design for a Perfume Bottle or Similar Article, of which the following is a specification, reference being had to the accompanying drawings forming part thereof, in which

Figs. 1 and 2 are side views respectively of the bottle and its cover;

Figs. 3 and 4 are plan views respectively of the bottle and cover;

Fig. 5 is a side view of the bottle and cover assembled.

I claim:

The ornamental design for a perfume bottle or similar article, as shown.

ROBERT BETTS.
